(57) **CLAIM**

The ornamental design for a display and storage rack, as
shown and described.

DESCRIPTION

FIG. 1 is a front elevational view of a display and storage
rack embodying the invention.

FIG. 2 is a rear elevational view of a display and storage rack
embodying the invention.

FIG. 3 is a top view of a display and storage rack embodying
the invention.

FIG. 4 is a bottom view of a display and storage rack
embodying the invention; and,

FIG. 5 is a left side view of a display and storage rack
embodying the invention, the right side view of said display
and storage rack being a mirror image thereof.

1 Claim, 4 Drawing Sheets
